UNITED STATES PATENT OFFICE

2,539,599

ADJUSTABLE WIRE STITCHER MECHANISM

Orville M. Tubbs, Chicago, Ill., assignor to Inland
Wire Products Company, Chicago, Ill., a corpora-
tion of Illinois

Application April 20, 1948; Serial No. 22,047

8 Claims. (Cl. 1—11)

1

This invention relates to an adjustable wire stitcher mechanism, and is particularly useful in connection with a machine for forming staples in cartons or other material to be stitched.

In wire stitching mechanism, as now constructed, a platform equipped with rollers is employed for supporting cartons and other objects to be stitched in a position for engagement with the stitching head of the machine. Adjustment of the platform to the desired estimated height requires the full attention of the operator and is time consuming. When a variety of cartons or other objects to be stitched are of different heights, considerable time is lost in adjusting the platform-supporting structure.

An object of the present invention is to provide a wire stitching mechanism in which the wire stitching operating parts are supported in a frame or head casing, which is mounted for movement in a stationary frame, the head being readily adjustable with one hand by the operator, so that time is not lost in the feeding of cartons of varying heights, etc. Yet another object is to provide a structure in which the stitcher mechanism and power unit therefor are supported in a balanced structure for vertical movement with a minimum of effort required of the operator. A still further object is to provide such a balanced structure which is equipped with cam followers or wheels which are brought into engagement with tracks for supporting the stitching mechanism against lateral or side movements. Yet another object is to provide adjustable means for modifying the counterbalance structure to meet changes in temperature and other changes. A still further object is to provide an adjustable shoe arrangement for use on the wire stitcher head. A still further object is to provide power-operated means for raising and lowering a slideably-mounted stitcher head casing, together with limit switches for bringing about an automatic stopping of the power unit. Yet another object is to provide a wire stitcher mechanism supported for movement with respect to a fixed platform and embodying novel construction parts. Other specific objects and advantages will appear as the specification proceeds.

The invention is illustrated, in a single embodiment, by the accompanying drawings, in which—

Figure 1 is a vertical sectional view of apparatus embodying my invention, the stitcher mechanism being removed at the forward end of the head casing; Fig. 2, a broken rear view in elevation; Fig. 3, a detail sectional view, the section being taken as indicated at line 3 of Fig. 1; Fig.

2

4, a transverse sectional view of the structure shown in Fig. 1; Fig. 5, a broken detail view showing a switch which may be supported by the head casing and used in connection with the electrically-operated elevating structure; Fig. 6, a view similar to Fig. 5, but showing a modified form of switch which is employed with the manually-operated elevating structure; Figure 7 is a fragmentary cross-sectional view through axis 1—1, Figure 4; Figure 8 is a fragmentary cross-sectional view through axis 8—8, Figure 1; and Figure 9 is a fragmentary exploded view of the shoe of Figure 4 and associated parts.

In the illustration given, A designates a casing having a base A¹. The casing is provided, at its forward side, as shown in Fig. 2, with an elongated slot 10 through which a head casing B may move in a vertical path.

The head casing B may be formed of a single casting, or it may be formed of several parts. It is equipped, at its forward end, with a wire stitcher or stapling mechanism 11, which is of well-known construction and which is not claimed per se herein. Below the stitcher mechanism 11 is a shoe 12, which is of well-known construction, and which is employed below the stitcher mechanism to provide an anvil for the turning of staples, etc. The shoe 12 is equipped with an upwardly-extending leg 13, through which extends a screw. The screw extends through a slot in the plate 14 of the wire stitcher mechanism to permit vertical adjustment of the leg 13 along the plate 14. An adjustment screw 15 is secured to the bottom wall of the casing B and extends through an opening in the horizontal flange 16 of the leg 13. Nuts, engaging the screw 15 on opposite sides of the flange 16, permit the flange 16 to be accurately adjusted in a vertical plane.

The casing B is equipped, at its rear, with a platform 17 upon which is supported a motor 18. The motor drives, through a pulley on its shaft, a belt 19 engaging the large pulley 20 on shaft 21. The shaft 21 drives, at its forward end, the wire stitching mechanism 11. Since the operation of the shaft and the operation of the wire stitching mechanism is well known, a detailed description is believed to be here unnecessary.

As shown more clearly in Fig. 1, the casing A is provided, on its inner side, with spaced tracks 22 and 23. These tracks are placed on each side of the casing facing each other. The casing B is provided, at its bottom, with a bracket 24 in which are supported rollers 25, which bear against the face of the tracks 22 and 23. Also supported

55

on the bracket 24 are two pairs of rollers 26, which are spaced apart on each side of the bracket 24 and engage the inner side wall of the tracks. Similarly, at the upper side of the casing B, there is a bracket 27 supporting rollers 28, which correspond to the rollers 25 of bracket 24, and rollers 29, which correspond to the rollers 26 of bracket 24.

A chain 30 is secured upon the lower end of the casing B, as shown in Fig. 1, and it extends downwardly about the sprocket 31. The chain extends also about another spaced sprocket 32 and is fixed to the rod 33 carried by a counterweight 34. A chain 35 is similarly fixed to the upper end of the counterweight 34 and extends upwardly and around sprockets 36 and 37 to the upper part of casing B. The sprockets 36 and 37 are mounted on idler shafts carried by a bracket 38 upon the top of the inner frame 39 within casing A.

Sprockets 31, 32, 35, and 37 define guide elements for the chain 30.

In securing the chain 30 upon the lower end of the head casing B, as shown in Figure 4, I provide a slideably-mounted rod 40 in the casing and in the depending bracket 24. The chain 30 is secured to the lower end of the rod. In turn, the rod is equipped with a nut 41 resting upon a compression spring 42 supported by a washer 43 on a sleeve 44. The nut 41 may be advanced or retracted along the threaded rod 40 to change the tension upon the chain 30.

The sprocket 31 is mounted upon a shaft 45, as shown more clearly in Fig. 4. The shaft 45 extends through the wall of the casing A and, on one side, is fixed to a brake hub or drum 46. The drum 46 is engaged by a brake arm normally urged against the drum by a spring. A solenoid 47 is arranged for drawing the brake arm away from the drum 46 to release shaft 45 for free rotation, when the solenoid is energized. A housing 48 may be provided to enclose the solenoid-operated brake illustrated. Since the solenoid-operated brake is of well-known construction, a detailed description is believed unnecessary.

The shaft 45 extends through the opposite wall of the casing A and is equipped with a flexible coupling 49 of well-known construction. If desired, the coupling may be disassembled to separate the motor from the shaft 45 for manual operating of the machine. Shaft 50 leading from the clutch 49 is equipped with a worm gear meshing with the worm 51, which is driven by motor 52, as shown more clearly in Fig. 2. The motor 52 drives the shaft 45 through coupling 49 for raising and lowering the chain 30, this drive being through the worm 51 and worm gear on shaft 50. When the coupling 49 is disconnected, the shaft 45 may rotate separately from shaft 50, and the apparatus may be manually operated.

In the manual operation of the elevating mechanism, a switch for controlling the solenoid 47 may be supported upon one side of the head casing B, as shown in Fig. 6. In this structure, there is a casing 53, in which is mounted a movable switch member 54 for closing the circuit of the solenoid. When the spring-urged member 54 is pressed inwardly, the circuit of the solenoid is closed and the brake upon shaft 45 released. The operator may then move the counterbalanced casing B readily upwardly or downwardly to the desired point. Upon release of the member 54, the solenoid circuit is opened, and the brake is applied by its spring to the drum of shaft 45 to maintain it against movement and thus to hold

the casing B in a fixed position for the operation of the stitching mechanism.

When it is desired to operate the apparatus by power, the coupling 49 is employed, as shown in Fig. 4. The switch 55, mounted in the casing 56 on the head casing B, is rotated to the right or the left, thus causing the reversible motor 52 to drive its shaft in one direction or the other. Just before the motor 52 is set into operation, the switch 55 closes the solenoid circuit so as to release the brake on shaft 45.

As shown more clearly in Fig. 1, the frame 39 is provided, at its upper end, with a limit switch 57 and in its bottom with a limit switch 58. These limit switches are also reversing switches and after being engaged permit travel of the casing B only in the opposite direction. Such switches are well known in the art. Such switches prevent the casing B from being driven against the end portions of the structure. I also provide a limit switch 59, as shown more clearly in Fig. 4, having a portion extending slightly below the shoe 12 carried by the stitcher mechanism 11. Should the operator be careless in lowering the head casing B, the limit switch 59, upon striking the carton or other object to be stitched, is effective for opening the circuit in which the motor 52 is placed, and thus eliminating downward movement of the head casing B. If desired, the limit switch 59 may also be placed within the circuit of the solenoid switch to open the circuit at this point and place the brake upon shaft 45.

As shown more clearly in Fig. 3, the sprocket 32 is mounted upon an idler shaft 60.

Operation

In the operation of the apparatus, assuming that the mechanism is to be operated manually and assuming that the head casing B is to be raised or lowered to adjust the shoe 12 to the height of a series of cartons, the operator, with his left hand, may move the switch 54 to energize the solenoid 47, while moving, with the same hand, the head casing B upwardly or downwardly to the desired point, and while at the same time using his right hand to feed the cartons forwardly under the stitcher mechanism 11. The motor 18 is controlled by a separate switch and may be operated continuously during the shifting operations described.

If the elevating mechanism is to be operated by power, the coupling 49 is employed, and switch 55 is turned to energize the solenoid circuit while closing the circuit of motor 52. The motor 52, depending upon the direction of rotation of its shaft, drives the shaft carrying sprocket 31 and thereby the chain 30 for elevating or lowering the head casing B to the desired point. Turning off of the switch 55 de-energizes the motor and, at the same time, de-energizes the solenoid circuit to again brake the shaft 45.

In each of the operations described, the counter-balance 34 makes the operation of the head casing B, with the parts supported thereby, extremely easy and one requiring little power. The chain tends to lengthen or to contract under temperature changes, and an adjustment for this may be made readily through the nut 41 engaging spring 42 on the rod 40.

The head casing B is supported firmly within the casing A and against thrusts in different directions by the rollers 25, 26, 28 and 29.

When it is desired to adjust the shoe 12 relative to the stitching mechanism 11 to meet the requirements of different types of cartons, etc.

which are to be stitched, the leg 13 may be raised or lowered, while modifying the position of the nuts on adjustment screw 15.

While, in the foregoing specification, I have set forth a specific structure in considerable detail for the purpose of illustrating one embodiment of the invention, it will be understood that such details of structure may be varied widely by those skilled in the art without departing from the spirit of my invention.

I claim:

1. In a wire stitching machine, a frame, a head casing slideably mounted in said frame for vertical movement, a counterbalance, sprocket wheels supported for rotation at the upper and lower ends of said frame, chain means engaging said sprocket wheels and connecting opposite ends of said head casing to opposite ends of said counterbalance, wire stapling mechanism carried by said head casing, and an adjustable spring connecting one end of said chain to one end of said head casing.

2. In a wire stitching machine, a frame, a head casing, wire stapling mechanism carried by said casing, a shoe extending below said casing and equipped with an upwardly-extending leg secured to said wire stapling mechanism in slideable relation thereto, said leg having a horizontally-extending flange, a screw carried by said casing and extending through said flange, and adjustment nuts on said screw and on opposite sides of said flange.

3. In a wire stitching machine, a frame, a head casing slideably mounted in said frame for vertical movement, guide elements at the upper and lower ends of said frame, a flexible member extending about said elements and connecting opposite ends of said casing, a brake for one of said elements, a solenoid for effecting release of said brake, and switch means in the circuit of said solenoid for closing said solenoid circuit to render said brake inoperative.

4. In a wire stitching machine, a frame, a head casing slideably mounted in said frame for vertical movement, guide elements at upper and lower ends of said frame, a counterbalance, a flexible member extending about said elements and connecting said counterbalance to opposite ends of said casing, a brake for one of said elements, a solenoid connected for releasing said brake when energized, and switch means in the circuit of said solenoid for closing said solenoid circuit to release said brake.

5. In a wire stitching machine, a frame, a

head casing slideably mounted in said frame for vertical movement, sprocket wheels mounted on shafts at upper and lower ends of said frame, a counterbalance, chain means engaging said sprocket wheels and connecting said counterbalance to said head casing, a brake for one of said sprocket wheel shafts, a solenoid for moving said brake to release position, and switch means in the circuit of said solenoid for closing 10 said circuit to render said brake inoperative.

6. In a wire stitching machine, a frame, a head casing slideably mounted in said frame for vertical movement, wire stapling mechanism carried by said head casing, means for raising and lowering said head casing, an electric motor for actuating said last-mentioned means, a brake controlling said last-mentioned means, a solenoid device for releasing said brake, and switch means for closing the circuit of said solenoid 20 and closing the circuit of said motor.

7. In a wire stitching machine, a frame, a head casing slideably mounted in said frame for vertical movement, wire stapling mechanism carried by said head casing, means for raising and lowering said head casing, an electric motor for actuating said last-mentioned means, brake mechanism controlling said last-mentioned means, a solenoid for releasing said brake, switch means for closing the circuit of said solenoid and closing the circuit of said motor, and switch means at the upper and lower ends of said frame adapted to be actuated by contact with said head casing for opening the circuit of said motor.

8. In a wire stitching machine, a frame, a head casing slideably mounted in said frame for vertical movement, wire stapling mechanism carried by said head casing, electric motor driven means for raising and lowering said head casing, and a limit switch depending from said head casing and adapted to be actuated by contact with an object to be stitched for opening the circuit of said motor.
